UNITED STATES PATENT OFFICE

120,479

DESIGN FOR A TOY

Andrew Bollak, New York, N. Y.

Application March 9, 1940, Serial No. 90,781

Term of patent 7 years

To all whom it may concern:

Be it known that I, Andrew Bollak, a citizen of the United States and a resident of New York city, county of New York, State of New York, have invented a new, original, and ornamental Design for a Toy, of which the following is a specification, reference being had to the accompanying drawing, forming part thereof, and in which:

I claim:

The ornamental design for a toy, as shown.

ANDREW BOLLAK.
